TOBACCO CURER WITH EXTINGUISHING
MEANS

Forrest Hildred Smith, Kinston, N. C.

Application August 15, 1947, Serial No. 768,764

2 Claims. (Cl. 126—93)

1

This invention relates to tobacco curers of the so-called open-flame oil burner type which are now widely used for curing bright tobacco. Examples of such curers are shown in my prior Patent No. 2,051,348. Such curers consist essentially of a large number of low intensity oil burners distributed across the barn floor so as to provide a uniform distribution of heat, each burner or group of burners being enclosed in a hood to prevent the direct heat from the flame impinging upon the over-hanging tobacco and also to insure a proper commingling of the products of combustion with the air admitted to the barn along the floor so as to reduce the temperature of the gases reaching the tobacco to the desired degree and also to prevent the housing reaching a temperature where it might become a fire hazard.

In carrying out the curing cycle which calls for several successive stages of temperature changes, the burners are adjusted so that no one burner, even at the highest temperatures which are required, generates sufficient heat to heat the metal of the hood to a temperature to involve any risk of igniting the dried tobacco or to a temperature where the tobacco immediately over the burner would be heated beyond the desired temperature. It happens sometimes, through carelessness or otherwise, that in adjusting the burners to effect the temperature change required by the curing cycle that some individual burner may be improperly adjusted and burn with abnormal intensity sufficient to overheat the hood of that particular burner or injure the tobacco immediately contiguous to it. Such abnormal operation of a single burner is insufficient to significantly affect the temperature of the barn as a whole, and consequently the operator might not be aware of this abnormal condition by inspection of the thermometers in the barn which are customarily read at intervals as the curing proceeds.

With the curers as at present constructed this hazard of a single burner getting out of adjustment can only be guarded against by periodic inspection of each burner and unless the inspections are frequent a fire may occur or the tobacco may be seriously damaged before the next inspection.

The object of the present invention is to provide in tobacco curers of the kind described, an attachment which will automatically extinguish the flame of any single burner immediately upon its developing an intensity beyond the maximum required for normal operation.

In practice the curers are supplied as individual

2

burners, that is, a single burner in each individual hood, as covered by my patent above mentioned, and also in groups of several burners to a common hood, as they are sometimes arranged, and my improved attachment is so designed so that it may be applied to both types of curers.

In the accompanying drawings I have illustrated a preferred form of my invention, and in the said drawings

10 Fig. 1 illustrates in vertical section a single burner equipped with one form of flame extinguishing attachment; and

15 Fig. 2 is a vertical longitudinal section through a multi-burner curer, the burners being shown at right angles to Fig. 1.

As shown in my prior patent and application above referred to, the curers consists of a number of individual oil burners arranged about the barn floor so as to provide an even distribution 20 of heat, the number of burners varying from twenty for a small barn to thirty or more for a barn of larger size. Each curer may consist of a single burner 5 (see Fig. 1) having its individual housing 6 and connected with a suitable supply 25 of fuel oil by a pipe indicated at 7. The burner shown has an asbestos wick and the intensity of the flame is secured in the customary manner by a wick-adjusting member 8, which raises and lowers the wick.

30 Surrounding and overlying each wick is a sheet metal collar 9 which serves in the customary manner to provide a combustion chamber around the wick so that when the burners are functioning properly the oil will burn with a blue flame 35 at various wick levels.

The hood or housing 6 consists of a sheet metal box of round or square cross section surrounding the burner and supported at the bottom by legs 10 for the ingress of air to the hood to supply the 40 oxygen for combustion and also to dilute the products of combustion so as to avoid excess temperatures. Each hood is provided with a conical cover 11 supported above the wall of the housing 6 by bars 12 as indicated, to permit the products

45 of combustion from the burner and the admixed air to flow outwardly in lateral directions and thence upwardly through the barn to heat the tobacco to the temperature desired. A door 13 is provided to give access to the burner for lighting and trimming.

50 The structure so far described constitutes a typical single burner unit as it is now used throughout the bright tobacco district. As stated above, in normal operation the burner is so adjusted that the temperature of the metal

forming the hood does not reach a point, even when the burner is set for the highest point desired in the curing cycle, to create a fire hazard even should the dried leaves of tobacco lodge directly on the surface of the hood. However, if the burner is not properly adjusted, as sometimes happens if the wick carbonizes unevenly, a single burner may develop a flame of abnormal intensity and create a fire hazard as well as overheat the immediately contiguous tobacco. In the form of my invention shown in Fig. 1, I provide a normally inoperative device for extinguishing an abnormal flame. This device consists of a metal plate 15 of a diameter slightly less than the diameter of the housing 6, the metal plate being suspended at its center from an eye 16 attached to the under side of the cover 11 at its apex. A cord 17 extends from the eye 16 through an eye-bolt 18 attached to the lower edge of the cover at one side, thence through a second eye-bolt 19 attached to one of the supporting bars 12 for the cover, and thence across the hood to a hook 20 attached to the bar 12 directly opposite the first mentioned bar 12, thus providing a length of stretched twine immediately overlying the flame of the burner. The twine selected is a soft cotton twine which will readily catch fire if the flame of the burner develops an intensity significantly above the desired maximum.

When the string burns in two as described, the metal plate 15 will drop onto the burner beneath and by closing off the opening in the draft collar 9 will extinguish the burner and prevent damage which otherwise might result. As the string is enclosed entirely within the hood the flame resulting from its ignition does no harm.

Extinguishing one burner of the twenty or thirty individual burners provided to supply the necessary heat does not significantly affect the distribution of the heat throughout the barn or the resulting temperature. If the temperature as a whole falls it will of course be noted by the operator on his periodic inspections and the extinguished burner will be promptly adjusted and re-lighted.

In Fig. 2 I have shown the above described extinguisher applied to the type of curing wherein several burners are enclosed in a single hood. In this type of curing three or more burners are enclosed in a single housing 24 of rectangular cross-section. Each burner 5 is equipped with its individual snuffing-plate 15 suspended over the burner by a cord 17 arranged to extend from side wall to side of the housing 24 immediately over the burner. If any one burner flares up to

an abnormal extent the cord immediately above it will be burned in two and the plate released before damage can be done and before the cords of the adjacent burners are heated to the ignition point.

In the foregoing specification and accompanying drawings I have described and illustrated a preferred form of my improved flame extinguisher, but it will of course be understood that the invention is not limited to the particular embodiment disclosed except insofar as recited in the appended claims.

I claim:

1. A heating device comprising a burner, a hood enclosing the burner and means for extinguishing the flame of the burner upon development of heat in excess of a predetermined value, said means comprising a metal plate suspended above the burner, a heat released member holding said plate in position above said burner, said member extending across the hood at a distance from the burner sufficient for the member not to be released by the heat of the burner when operating at the desired intensity but near enough to be released by the heat of the burner when the intensity of the heat rises significantly above such predetermined value.

2. A heating device comprising a burner, a hood enclosing said burner and means for extinguishing the flame of said burner upon its development of heat in excess of a predetermined value, comprising a snuffing plate, an inflammable member supporting said snuffing plate above said burner, said inflammable member extending across the path of the combustion products from said burner at a distance from said burner sufficient for the member not to be ignited from the heat of the burner when operating at the desired intensity but near enough to be ignited when the heat from the burner rises significantly above such predetermined value.

FORREST HILDRED SMITH.
